UNITED STATES PATENT OFFICE.

FRANK O. BEUERMANN, OF NEW YORK, N. Y.

MOUTHPIECE FOR TELEPHONES.

1,008,522.

Specification of Letters Patent. Patented Nov. 14, 1911.

Application filed November 11, 1910. Serial No. 591,771.

To all whom it may concern:

Be it known that I, FRANK O. BEUERMANN, a citizen of the United States, and resident of the borough of Brooklyn, county of Kings, city and State of New York, have invented certain new and useful Improvements in Mouthpieces for Telephones, of which the following is a specification.

My invention relates to mouth pieces for telephones and has for its object to provide a mouth piece made of porcelain or other similar material which forms a perfect non-conductor, is readily and easily kept clean and antiseptic and further is not readily broken or chipped.

A further object of my invention is to combine said mouth piece with a metallic attaching device in a simple and effective manner so that the said mouth piece may be securely and yet removably fastened to the telephone proper.

My invention will be fully described hereinafter and the features of novelty will be pointed out in the appended claims.

Reference is to be had to the accompanying drawings in which—

Figure 1 is an elevation of my improved mouth piece with parts broken away; Fig. 2 is a sectional view thereof on the line 2—2 of Fig. 1; Fig. 3 is an end view of the mouth piece proper and Fig. 4 is a perspective view of the metallic fastening ring.

In carrying out my invention the body 1 of the mouth piece is made in the usual flaring bell shape and is preferably formed of porcelain although other similar material may be substituted if desired. The usual perforated partition 2 is provided adjacent to the small end of said mouth piece, said partition being preferably integral with said mouth piece. An annular channel 3 is formed in said mouth piece at its inner or small end by providing an annular partition 4 spaced from the inner surface of said mouth piece and surrounding the perforations in the partition 2. At one point in the annular channel 3 a preferably integral lug or projection 5 is provided for the purpose to be more fully described hereinafter. In order to permit the said mouth piece to be removably secured in operative position on the telephone I provide a metallic ring 6 having its entire outer surface screw threaded and provided with a recess 7 arranged to operate with the projection 5 as will appear more fully farther on in the description.

The one end of said ring 6 is first dipped into a suitable cement or other binder 6^a and then inserted into the channel 3 with the recess 7 placed over the projection 5 in which position the cement is permitted to set and thus secure the ring 6 firmly in position. By having the ring 6 screw threaded throughout its outer surface the cement or other binder will enter some of said screw threads or rather the spaces therebetween and thus serve as a positive means for preventing the withdrawal of the ring from the channel 3. In other words a roughened surface is provided which affords a firm footing or foundation for the binder so that the mouth piece and the fastening ring are securely fastened together and form a substantially single structure. I desired an additional annular groove 8 may be provided on the inner surface of the mouth piece at a point just inside its inner end into which the cement or other binder may find its way to provide a still further lock against the removal of the metallic ring. Should the cement or other binder from some cause become ineffective in time and the ring 6 become loosened the projection 5 and recess 7 will prevent relative rotation or lateral movement between the ring 6 and mouth piece 1 so that said ring may be unscrewed from the telephone by manipulating the mouth piece. After this has been done the said ring may be removed from the mouth piece and re-dipped in a fresh binder and again connected with the mouth piece as above described or a new ring may be substituted. It is of course to be understood that methods of applying the cement other than the one described herein may be used and that said ring 6 may be first inserted into the channel 3 and the binder then suitably applied as by pouring if desired. The axial length of the ring 6 is such that when it is in position on the mouth piece a portion of said ring will project beyond the inner end of the mouth piece so as to be exposed. This exposed portion of the ring is adapted to be screwed into the transmitter in the usual manner and serves to secure the mouth piece in operative position. The ring 6 is further provided with the usual vents 9 for preventing sudden excessive pressure, as by sudden gusts of air, from disarranging the usual diaphragm and carbon particles.

My invention thus provides a simple means for firmly and rigidly securing the

mouth piece and fastening ring together. In addition to utilizing some of the screw threads on the ring as an aid for securing said ring in position, the cost of the ring is reduced by screw threading the entire outer surface instead of leaving a portion thereof smooth as heretofore. The present construction also does away with the necessity for careful manipulation of the threading machine in order not to encroach on the usual smooth portion.

10 The advantages of the porcelain mouth piece are its capability of being readily and easily kept clean and its non-porosity so that it will not catch dust, disease germs and the like. It is also not as brittle as the customary mouth piece and will therefore not break as readily.

20 Various changes in the specific form shown and described may be made within the scope of the claims without departing from the spirit of my invention.

I claim:

1. A mouth piece for telephones comprising a body portion having at its one end an annular groove extending inwardly from the one end face of said body portion, attaching means arranged to be inserted into said groove and means for securing said attaching means in said groove.

2. A mouth piece for telephones comprising a body portion having an annular recess adjacent to its one end, attaching means extending axially into said recess and having the portion of its outer surface which is within said recess roughened and a binder adapted to coöperate with said roughened portion to secure the attaching means in position.

3. A mouth piece for telephones comprising a body portion having an annular recess adjacent to its one end, a projection in said

recess and attaching means extending into said recess and having a recess adapted to coöperate with said projection to prevent relative lateral movement between the body and the attaching means.

4. A mouth piece for telephones comprising a body portion having an annular recess adjacent to its one end, attaching means extending into said recess and coöoperating means located respectively on said body and said attaching means for preventing relative lateral movement between said body and means.

5. A mouth piece for telephones comprising a body portion having an annular recess adjacent to its one end an attaching ring extending into said recess and having its outer surface screw-threaded throughout and a binder adapted to coöperate with some of said screw-threads to secure said ring in position.

6. A mouthpiece for telephones comprising a body portion and attaching means slidable one over the other in the direction of their common axis and means located between adjacent surfaces of said body portion and attaching means for securing said body portion and attaching means together.

7. A mouthpiece for telephones comprising a body portion having a recess on one end and attaching means having a portion projecting into said recess and means separate from said body portion and attaching means for securing them together.

In witness whereof I have hereunto set my hand in the presence of two subscribing witnesses.

FRANK O. BEUERMANN.
